STEAM VACUUM FINISHER

William C. Glover, Jr., Kansas City, Mo., assignor to Bill Glover Incorporated, a corporation of Missouri

Application February 18, 1946, Serial No. 648,267

3 Claims. (Cl. 68—6)

1

This invention relates to improvements in steam vacuum finishers and refers more particularly to a device used in dry cleaning establishments subsequent to dry cleaning operations to give the garments a more finished appearance.

The dry cleaning of garments often causes the nap or pile of the fabric to become mussed, crushed or flattened and to lose its original gloss. To reinstate the fabric to its original condition cleaners resort to many types of finishing operations, perhaps the most successful consisting in steaming the garments and drying out the steam by drawing air through the fabric.

The finisher hereinafter described provides a device admirably adapted to such purposes since the working surface to which the fabrics are applied during steaming and drying is kept constantly heated.

An object of the invention, therefore, is to provide a steam vacuum finisher wherein live steam used for finishing fabrics is first passed through a coil or radiator in heat exchange relation with the working surface of the finisher to maintain the surface at a desired temperature and prevent objectionable condensation of the live steam admitted during the finishing operation.

Another object is to provide an enlarged foraminous plate or screen arranged above a shallow pan into which steam is introduced and discharged over an extensive area and through which drying air may be drawn after the steaming operation.

Other and further objects will appear from the following description.

In the accompanying drawing which forms a part of the instant specification and is to be read in conjunction therewith and in which like reference numerals indicate like parts in the various views,

Fig. 1 is a sectional elevational view of a finisher embodying the features of the invention.

Fig. 2 is a fragmentary rear elevation of a portion of the steam separator showing the controls for the steam and vacuum operations, and

Fig. 3 is a view taken along the line 3—3 in Fig. 1.

In the drawings, wherein for the purpose of illustration is shown a preferred embodiment of the invention, the numeral 10 designates a pedestal with an enlarged base 10a. On top of the pedestal is a shallow pan 11 covered by a perforated plate or foraminous screen 12. This plate or screen is centrally braced within the pan by a flanged web 13 running longitudinally of the

2

pan. Beneath the screen or perforated plate and attached thereto by means of clips 14 is a radiator made up of a plurality of lengths of steam pipe 15 forming a continuous passageway for the steam from inlet pipe 16 to outlet pipe 17.

The inlet pipe 16 is joined to a steam supply pipe 18 by the reducer connection 19.

Supported on the side of the pedestal is a steam separator 20 into the bottom of which is connected a liquid draw-off line 21. The discharge pipe 17 from the radiator or heating coil 15 is connected into the lower portion of the separator at an elbow joint 17a. Into the upper portion of separator 20 is connected a steam discharge pipe 22 branching to form the separate steam lines 23 and 24. In pipe 23 is interposed a valve 25 and in pipe 24 a valve 26. The open discharge end of pipe 23 is beneath a baffle 27 located in the pedestal end of pan 11. This baffle comprises a box-like structure closed on all sides except the front so steam discharged from the pipe is directed longitudinally of the pan. Pipe 24 is connected into a vacuum injector device 28 which also has an open connection with the pan beneath the baffle. Steam supplied to the injector through pipe 24 creates vacuum conditions within the pan and draws air down through the perforated plate or screen 12 covering the pan.

Controls for actuating valves 25 and 26 are manipulated from a tilting pedal 29 pivoted at 30 to the base 10a of the pedestal. Attached to the pedal pivot is a vertical lever 31 connected through a link 32 with a pivoted arm 33 carried by a support 34. To the opposite end of the pivoted arm 33 is fastened a vertical rod 35 to which are adjustably attached by set screws a lower collar 36 and an upper collar 37. Valve 26 has a depending bracket 38 to which is pivoted a horizontal arm 39. The free end of the arm has an eye or ring into which is fitted the vertical rod 35. In mounting this rod the collar 36 is positioned below the valve actuating arm 39. Valve 25 has an upright bracket 40 to which is pivoted a valve-actuating arm 41. The free end of this arm likewise has an eye or ring through which the vertical actuating rod 35 passes. In the assembly of the control, collar 37 is located above the link at the end of actuating arm 41. Extending horizontally from the front of the pedestal is a loop-shaped frame 42 to which is laced a canvass garment catcher. A second pedal 43 pivoted at the front of the pedestal rotates rod 44 to operate a valve not shown 55 which is connected into the upper part of the

separator at plug 45 when a steam iron is used with the finisher. A steam iron plate 46 is provided at the rear of the pan on top of the pedestal.

When finishing garments the operator stands at the side of the finisher with his foot on tilting pedal 29. The garment or fabric to be finished is placed on the perforated top of the pan and steam is flushed through the fabric by pressing down on the pedal to the left of pivot 30. This tilts vertical lever 31 to the left moving link 32 horizontally to the left and depressing the lower end of rod 35. As rod 35 is lowered collar 37 depresses actuating arm 41 which in turn depresses the spring operating pin in valve 25 opening the valve and permitting steam to be discharged beneath baffle 27 through pipe 23. The steam sweeps along the entire length of the pan and is discharged through the perforations in the top. When it is desired to follow the steam operation with an air-drying operation the operator steps on pedal 29 to the right of pivot 30. This moves upright lever 31 and link 32 to the right tilting arm 33 so vertical rod 35 is pushed upwardly. Collar 36 acts upon actuating arm 39 raising the operating pin of valve 26 and discharging steam through pipe 24 into injector 28. The steam injector imposes a vacuum upon the pan and drying air is drawn down through the fabric lying upon the perforated top of pan 11.

Since steam supplied to separator 20 is introduced through pipe 18 and circulates first through radiator 15 the temperature within the pan and particularly the temperature of the perforated plate or screen covering the pan is maintained relatively high and above temperatures which cause objectionable condensation within the pan.

It is recognized that heretofore a steam radiator or heating coil has been mounted in pans of dry cleaners finishing machines but when so used the coils are supported in the lower portion of the pan either resting upon the bottom of the pan or upon braces or brackets affixed to the bottom of the pan. In the instant device the steam radiator or heating coils have been purposely clipped or attached in heat exchange relation with the foraminous screen or perforated plate covering the pan so the heat will be concentrated at the upper surface where serious and objectionable condensation occurs. Discharge pipe 21 for removing condensate from the separator is connected into a suitable trap arrangement not shown.

From the foregoing it will be seen that the invention is one wall adapted to attain all of the ends and objects hereinabove set forth together with other advantages which are obvious and which are inherent to the device.

It will be understood that certain features and subcombinations are of utility and may be employed without reference to other features and subcombinations. This is contemplated by and is within the scope of the claims.

As many possible embodiments may be made of the invention without departing from the scope thereof it is to be understood that all matter herein set forth or shown in the drawings is to be interpreted as illustrative and not in a limiting sense.

Having thus described my invention I claim:

1. A steam vacuum finisher comprising a pedestal, a shallow pan supported thereby, a foraminous sheet covering the pan, a heating coil within the pan in heat exchange relation with said sheet, a nozzle for injecting an open steam supply into the pan beneath the foraminous sheet, a steam vacuum injector connected with the pan for imposing vacuum conditions on the pan, a steam separator carried by the pedestal and pipe connections for introducing steam to the separator through the coil, separate steam supply lines from the separator to the nozzle and from the separator to the vacuum injector, and controls optionally operable for separately delivering steam to the nozzle and vacuum injector.

2. A steam vacuum finisher as in claim 1 in which the optional controls comprise steam connections between the separator and nozzle and between the separator and vacuum injector, a valve in each steam connection, an actuating pedal common to the valves and movable in either direction from a neutral position, and linkage from the pedal to the valves adapted to open only one valve when the pedal is moved in one direction from neutral and to open only the other valve when the pedal is moved in the other direction from neutral.

3. A steam vacuum finisher comprising a pedestal, a shallow pan supported thereby, a foraminous sheet covering the pan, a heating coil within the pan in heat exchange relationship with said sheet, a nozzle for injecting an open steam supply into the pan beneath the foraminous sheet, a steam vacuum injector connected to the pan for imposing vacuum conditions on the pan, an actuating device common to the nozzle and the injector movable in either direction from a neutral position, and valve means controlled by the actuating device to supply steam only to the nozzle when the device is moved in one direction from neutral and to supply steam only to the injector when the device is moved in the other direction from neutral.
